UNITED STATES PATENT OFFICE.

CHARLES L. DUNHAM, OF CENTRE VIEW, OHIO.

PIPE-WRENCH.

SPECIFICATION forming part of Letters Patent No. 656,154, dated August 14, 1900.

Application filed June 6, 1900. Serial No. 19,272. (No model.)

To all whom it may concern:

Be it known that I, CHARLES L. DUNHAM, a citizen of the United States, residing at Centre View, in the county of Monroe and State of Ohio, have invented certain new and useful Improvements in Pipe-Wrenches; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention has relation to improvements in pipe-wrenches; and it consists in the novel construction, combination, and arrangement of parts of which it is composed, all as will be hereinafter more fully explained, and particularly pointed out in the appended claims.

The annexed drawings, to which reference is made, fully illustrate my device, in which—

Figure 1 represents a side view of my wrench, partly in section. Fig. 2 is an edge or top view of the same, and Fig. 3 is an edge or bottom view.

Referring by letter to the accompanying drawings, A designates the wrench, which is composed of several parts pivoted to one another, the portion a being the lever that is pivoted to the portion b, while the latter in turn is pivoted to an intermediate portion c, which is also pivoted to the portion d, that is free and independent of the other sections and is interposed between the section c and the lever when the device is in operation. The lever a is provided with an opening e, near its inner end, of peculiar shape, the inner end of the lever being constructed with an enlargement f, in which this opening is arranged, said opening being of an irregular form, the forward portion g being much smaller in size than the opposite portion h, while the lower surface thereof curves upward, as at i, and the upper surface curving downward, as at j, presenting an opening in the inner end of the lever, which has a narrow portion and an enlarged portion, and the whole providing a seat for the pivotal pin, by which said lever is fulcrumed to the section b, and this lever is further provided with a projection or nose k at the extreme inner end that engages one of the interlocking lugs on

the section d, further hereinafter explained. To the inner end of the lever aforesaid is pivoted one end of a skeleton or forked iron l by 55 a transverse bolt m, that passes through eyes n in said iron and through the peculiar-shaped opening in the lever, and this iron is forked at both ends, the same being joined by a solid bridge o, the whole formed integral. 60 This skeleton iron is constructed with downward-curved side flanges p p in the form of a segment, and the twin ends q q are provided with transverse perforations or eyes r r, through which a bolt or pin s passes, which 65 also passes through a transverse perforation in one end of the link u of the series of links c, and the end v of the end link w is pivoted to the outer end of the section d, as at x, thereby in such construction connecting or 70 pivoting the several sections to one another. The section d is of a peculiar shape and resembles in form somewhat the letter J, the same having the inner-curved face, which curve starts from the point y near its pivotal 75 point and gradually curves upward and outward to the point z. The outer face of said section is provided with a series of lugs a', between which are curved spaces b', which correspond in shape with the shape of the point 80 or nose and inner-curved portion of the lever, as at c'.

Having thus described the various parts of which my device is composed, I will now proceed to explain its operation.

In using my pipe-wrench the operator passes the pivotal sections around the pipe in the usual manner, the free end of the section d entering the space between the side flanges of the skeleton iron that provides a guide-way for said section and prevents any lateral movement thereof, after which the nose of the lever is brought into engagement with said section by engaging one of the lugs and interlocking therewith, when the handle portion of the lever is brought down, which causes the lever to turn upon its fulcrum, thereby raising the nose, which in turn causes the section d to rise upwardly and at the same time inward, thus binding the pipe 100 within the opening of the sections, and the harder the pressure applied to the handle the firmer the sections will grasp the object between them. It will be observed from the

above description and by reference to the annexed drawings that in constructing my pipe-wrench I dispense with any and all attachable parts, such as teeth or serrated 5 parts, for the gripping portions of the sections, and by the peculiar construction of the opening in the lever I am enabled to produce a power and pressure upon the section *d* which will cause the grasping-sections to 10 firmly bind the pipe, and this powerful pressure is obtained by reason of the fulcrum-pin first coming in contact with the upper inner curved wall of the opening in the lever, and when the handle is pressed down a 15 wedge-like contact is obtained between the pin and wall, thereby giving the nose or point of the lever the benefit of a compound forcing movement. At the same time the curve of the nose in contact with the curve between 20 each interlocking lug also has a wedging-movement, presenting a firm grip of the pivoted sections. At the same time the enlarged portion of the opening in the lever permits said lever to accommodate itself to the different-sized pipes to which the wrench may be applied—that is to say, should the pipe be 25 very large the fulcrum-pin would find its own seat at a certain point within the opening corresponding with the expansion of the 30 pivoted sections, and when said pipe is about the same diameter as the opening between the sections the fulcrum-pin will be seated in the narrow end thereof; and it will also be seen that in constructing the inner-curved 35 faces of each section the curvature is struck to one side of a common center, thereby presenting a different curved or grasping portion to that of the pipe to be turned.

I do not wish to be confined to the exact 40 constructions of my pipe-wrench, as various changes may be made in its construction

without departing from the spirit of my invention. For instance, one or more interlocking lugs may be used and one or more links may be dispensed with and the section *d* pivoted directly to the skeleton frame, and a device as herein shown and described is simple in operation, durable, and at the same time cheap to manufacture. 45

Having thus described my invention, what I claim, and desire to secure by Letters Patent, is— 50

1. In a pipe-wrench, the combination with the skeleton frame, connecting-links and lever, of the section *d* having the gradual inner curve and provided with the interlocking lugs, the curved point adapted to engage 55 said lugs, and the opening, comprising a small and large space to receive the fulcrum-pin, substantially as described. 60

2. In a pipe-wrench, the combination of the skeleton frame, and links, of the lever provided with the nose and opening, the latter having the enlarged curved portion and narrow portion, the section *d* having the inner-curved face and interlocking lugs on its outer 65 face adapted to engage the nose of the lever, substantially as described. 70

3. In a pipe-wrench, the lever provided with the opening, comprising different-sized spaces and having a projection, in combination with the section having the inner gradual-curved face and outer-curved interlocking lugs, the skeleton frame and connecting-links, all substantially as described. 75

In testimony whereof I affix my signature in presence of two witnesses.

CHARLES L. DUNHAM.
